Primary Examiner — David Muller(74) *Attorney, Agent, or Firm* — Head, Johnson & Kachigian, P.C.(57) **CLAIM**

The ornamental design for a vent pipe protector for standing seam roofs, as shown and described.

DESCRIPTION

FIG. 1 is a perspective view of a vent pipe protector constructed in accordance with the present invention shown installed on a standing seam roof (shown in dashed lines) and an upstanding vent pipe (shown in dashed lines);

FIG. 2 is a perspective view of the vent pipe protector apart from the roof and vent protector;

FIG. 3 is a top plan view thereof;

FIG. 4 is a bottom plan view thereof;

FIG. 5 is a right side elevation view thereof;

FIG. 6 is a left side elevation view thereof;

FIG. 7 is a rear elevation view thereof; and,

FIG. 8 is a front elevation view thereof.
